(57) **CLAIM**

The ornamental design for a transmission cooler for automotive applications, as shown and described.

DESCRIPTION

FIG. 1 is a front view of a transmission cooler for automotive applications showing our new design;

FIG. 2 is a back view thereof;

FIG. 3 is a right view thereof;

FIG. 4 is a left view thereof;

FIG. 5 is a top view thereof;

FIG. 6 is bottom view thereof; and,

FIG. 7 is a perspective view thereof.

The shade lines in the figures show contour and not surface ornamentation.
